US00D770143S

(12) **United States Design Patent** (10) **Patent No.:** **US D770,143 S**
Waters (45) **Date of Patent:** ** *Nov. 1, 2016

(54) BEANIE WITH MEANS FOR ILLUMINATION	2,196,543 A	4/1940	Anderson
	2,373,553 A	10/1942	Fetterman
	D137,375 S	2/1944	Heit
	2,369,829 A	2/1945	Johnson
	2,461,254 A	2/1949	Bassett
	2,473,394 A	6/1949	Scott
(71) Applicant: Michael Waters , Aspen, CO (US)	2,531,585 A	11/1950	Pope
(72) Inventor: Michael Waters , Aspen, CO (US)	2,540,435 A	2/1951	Ferguson
(*) Notice: This patent is subject to a terminal disclaimer.	2,552,764 A	5/1951	Bedford, Jr.
	2,567,046 A	9/1951	Anderson
	2,591,112 A	4/1952	Zwierzynski
	2,638,532 A	5/1953	Brady
(**) Term: 14 Years	2,640,980 A	6/1953	Prupis
(21) Appl. No.: 29/491,782	2,705,751 A	4/1955	Harris
(22) Filed: May 23, 2014	2,730,720 A	1/1956	Saunders
(51) LOC (10) Cl. 02-03	2,788,439 A	4/1957	Hesse

CLAIM

I claim the ornamental design for a beanie with means for illumination, as shown and described.

DESCRIPTION

FIG. 1 is a perspective view of a beanie with means for illumination, according to my new design;

FIG. 2 is a front elevational view thereof;

FIG. 3 is a bottom plan view thereof;

FIG. 4 is a top plan view thereof;

FIG. 5 is a perspective view of a second embodiment of the beanie with means for illumination, according to my new design;

FIG. 6 is a front elevational view thereof;

FIG. 7 is a bottom plan view thereof;

FIG. 8 is a top plan view thereof;

FIG. 9 is a perspective view of a third embodiment of the beanie with means for illumination, according to my new design;

FIG. 10 is a front elevational view thereof;

FIG. 11 is a bottom plan view thereof;

FIG. 12 is a top plan view thereof;

FIG. 13 is a perspective view of a fourth embodiment of the beanie with means for illumination, according to my new design;

FIG. 14 is a front elevational view thereof;

FIG. 15 is a bottom plan view thereof;

FIG. 16 is a top plan view thereof;

FIG. 17 is a perspective view of a fifth embodiment of the beanie with means for illumination, according to my new design;

FIG. 18 is a front elevational view thereof;

FIG. 19 is a bottom plan view thereof;

FIG. 20 is a top plan view thereof;

FIG. 21 is a perspective view of a sixth embodiment of the beanie with means for illumination, according to my new design;

FIG. 22 is a front elevational view thereof;

FIG. 23 is a bottom plan view thereof;

FIG. 24 is a top plan view thereof;

FIG. 25 is a perspective view of a seventh embodiment of the beanie with means for illumination, according to my new design;

FIG. 26 is a front elevational view thereof;

FIG. 27 is a bottom plan view thereof;

FIG. 28 is a top plan view thereof;

FIG. 29 is a perspective view of an eighth embodiment of the beanie with means for illumination, according to my new design;

FIG. 30 is a front elevational view thereof;

FIG. 31 is a bottom plan view thereof;

FIG. 32 is a top plan view thereof;

FIG. 33 is a perspective view of a ninth embodiment of the beanie with means for illumination, according to my new design;

FIG. 34 is a front elevational view thereof;

FIG. 35 is a bottom plan view thereof;

FIG. 36 is a top plan view thereof;

FIG. 37 is a perspective view of a tenth embodiment of the beanie with means for illumination, according to my new design;

FIG. 38 is a front elevational view thereof;

FIG. 39 is a bottom plan view thereof;

FIG. 40 is a top plan view thereof;

FIG. 41 is a perspective view of an eleventh embodiment of the beanie with means for illumination, according to my new design;

FIG. 42 is a front elevational view thereof;

FIG. 43 is a bottom plan view thereof;

FIG. 44 is a top plan view thereof;

FIG. 45 is a perspective view of a twelve embodiment of the beanie with means for illumination, according to my new design;

FIG. 46 is a front elevational view thereof;

FIG. 47 is a bottom plan view thereof;

FIG. 48 is a top plan view thereof;

FIG. 49 is a perspective view of a thirteenth embodiment of the beanie with means for illumination, according to my new design;

FIG. 50 is a front elevational view thereof;

FIG. 51 is a bottom plan view thereof;

FIG. 52 is a top plan view thereof;

FIG. 53 is a perspective view of a fourteenth embodiment of the beanie with means for illumination, according to my new design;

FIG. 54 is a front elevational view thereof;

FIG. 55 is a bottom plan view thereof;

FIG. 56 is a top plan view thereof;

FIG. 57 is a perspective view of a fifteenth embodiment of the beanie with means for illumination, according to my new design;

FIG. 58 is a front elevational view thereof;

FIG. 59 is a bottom plan view thereof;

FIG. 60 is a top plan view thereof;

FIG. 61 is a perspective view of a sixteenth embodiment of the beanie with means for illumination, according to my new design;

FIG. 62 is a front elevational view thereof;

FIG. 63 is a bottom plan view thereof;

FIG. 64 is a top plan view thereof;

FIG. 65 is a rear elevational view of each of the first through sixteenth embodiments of the beanie with means for illumination;

FIG. 66 is a left side elevational view of each of the first through sixteenth embodiments of the beanie with means for illumination; and,

FIG. 67 is a right side elevational view of each of the first through sixteenth embodiments of the beanie with means for illumination.

The broken lines shown in the drawings illustrate portions of the beanie with means for illumination that form no part of the claimed design.
